CLAIM

The ornamental design for a rocket-shaped medical patch as shown and described.

DESCRIPTION

FIG. 1 is a front perspective view of a rocket-shaped medical patch of the present design.

FIG. 2 is a front view of the medical patch of FIG. 1.

FIG. 3 is a rear view of the medical patch of FIG. 1.

FIG. 4 is a right-side view of the medical patch of FIG. 1, wherein the left-side view of the medial patch is a mirror image of the right-side view.

FIG. 5 is a top view of the medical patch of FIG. 1; and,

FIG. 6 is a bottom view of the medical patch of FIG. 1.

(Continued)

The broken lines shown in the drawings illustrate portions of the medical patch that form no part of the claimed design.
